DENTAL TRAY

William Edelman, 504 S. Spring, Tyler, Tex.

Filed May 24, 1962, Ser. No. 70,274

Term of patent 14 years

(Cl. D24—1)

FIG. 1

FIG. 2

FIG. 3

FIG. 4

FIG. 5

FIG. 6

FIG. 7

FIG. 1 is a top plan view of a dental tray embodying my new design,

FIG. 2 is a side elevational view of the dental tray,

FIG. 3 is a vertical, cross-sectional view taken upon the line 3—3 of FIG. 1,

FIG. 4 is a vertical, cross-sectional view of the line 4—4 of FIG. 1,

FIG. 5 is a bottom plan view of the dental tray,

FIG. 6 is a side elevational view taken at right angles to FIG. 2, and

FIG. 7 is a vertical cross-sectional view taken on the line 7—7 of FIG. 1.

I claim:

The ornamental design for a dental tray, as shown.
